UNITED STATES PATENT OFFICE.

RAYMOND R. LIGOT, OF BRUSSELS, BELGIUM, ASSIGNOR OF ONE-HALF TO JAMES PULEO, OF NEW YORK, N. Y.

ACETYLENE GENERATOR.

Application filed November 5, 1920. Serial No. 421,836.

To all whom it may concern:

Be it known that I, RAYMOND R. LIGOT, a subject of the King of Belgium, residing at Brussels, in Belgium, have invented a certain new and useful Acetylene Generator, of which the following is a specification.

This invention relates to the art of generating acetylene gas and is directed to a novel apparatus.

In prior processes for carrying out the generation of acetylene gas, water is commonly fed to calcium carbide and this amount of water is often controlled by valves, so that only such amount of water is allowed to pass the valve as will be required to produce the desired amount of gas. Such processes are unsatisfactory for many reasons, chief among which is the inability to properly regulate the water with the result that too much water is fed and the calcium carbide acted upon too rapidly so that it becomes flooded and considerable carbide is wasted in this manner. Moreover, in the practicing of practically every prior process, it is necessary to shut down the apparatus from time to time in order to remove the ash or replenish the carbide.

With these considerations in mind, the object of the present invention is to provide an apparatus for carrying out a process for generating acetylene gas by automatically controlling the supply of water to the calcium carbide by back pressure operating through a column of oil, whereby, in the event too much water is fed to the carbide, the rapid generation of gas which results builds up a back pressure which operates upon a body of oil to automatically force back the water from the carbide. In this manner, by controlling the pressure, the action of the water on the carbide may be accurately controlled and regulated so as to obtain maximum efficiency and economy in the process.

A further object of the invention is to provide an apparatus, wherein the foregoing process may be carried out, in a simple, economical and efficient manner, and wherein the operation of generating the gas may be carried on continuously and without interruption through the provision of means for replenishing the calcium car-

bide and removing the ash while the apparatus is operating.

Features of the invention, other than those adverted to, will be apparent from the hereinafter detailed description and claims, when read in conjunction with the accompanying drawings.

The accompanying drawings illustrate in central vertical section one form of apparatus which may be employed to carry out the process of this invention, but the construction therein shown is to be understood as illustrative, only, and not as defining the limits of the invention.

In the drawing, 1 designates a vessel preferably cylindrical in form, provided with a sloping bottom 2 having at its center an inverted frustro conical outlet 3. The vessel 1 is provided with a flared top 4 which may, for the purpose of this invention be left open so as to permit water to be readily poured into the vessel. The outlet 3 at the bottom of the vessel is preferably closed by a conical valve 5 provided with a stem 6. The vessel is supported on any suitable base 7 through which may be extended a rock shaft 8 having a laterally extending arm secured to the stem 6 of the valve and provided at one of its ends with a crank 9 by means of which the rock shaft may be oscillated for the purpose of raising or lowering the valve 5 to allow the contents of the vessel to be discharged from the outlet 3 or to seal the outlet 3 against such discharge.

Positioned within the vessel 1 is an inverted dome 10, cylindrical in form with a closed top and an open bottom and of such diameter that the side walls of the dome are spaced from the side walls of the vessel 1. The dome is suspended within the vessel by means of a plurality of brackets 11 and the interior of such dome constitutes the gas generating chamber. Adjacent the lower end of the dome and on the interior thereof are brackets 12, on which is adapted to rest a tray or container 13 for holding the calcium carbide. The top of the tray 13 is open and the bottom thereof is perforated or foraminous as shown.

A pipe 14 extends through the closed top of the dome 10 from a point above the upper edge of the flared top 4 of the vessel and downwardly into the vessel to a point

just above the top of the tray and through this pipe 14 carbide and oil may be introduced. In order that the carbide may be properly distributed throughout the tray, 5 a deflector 15 is positioned above the tray and supported on a tubular standard 16, the lower end of which is rigid with the bottom of the tray, whereby carbide introduced into the apparatus through the pipe 14 strikes the deflector and falls evenly 10 throughout the tray.

In practice, water is introduced into the vessel and with the valve 5 seated, the level of such water may be readily noted by a 15 suitable sight gauge 17 associated with the vessel as shown. Thereafter oil 18 and carbide 19 are introduced through the pipe 14. The carbide settles into the tray 13 and a generation of gas commences immediately. 20 Because of the position of the deflector 15, the gas does not find exit through the pipe 14, but rises to the top of the dome, where it finds exit through a pipe 20. This pipe is provided with a valve 21, which is 25 so regulated that back pressure will result in the top of the dome. The oil introduced into the dome will stratify, and the back pressure referred to will act upon the oil which, operating as a piston, will force the 30 water level in the dome downwardly. By regulating the valve 21 to control the amount of back pressure, the oil piston is caused to force the water level within the dome downwardly to such extent that the 35 water will attack the carbide only to the degree desired and not to such extent as to cause flooding of the carbide and consequent excess generation of the gas.

Through the regulation of the valve 21, 40 the action of the water on the carbide may be accurately controlled, so as to generate the amount of gas desired and not build up excess back pressure. In the event, of too quick action of the water on the carbide, the 45 back pressure will become greater forcing the oil piston downwardly so that the water is forced out of contact with the carbide. The oil will then envelop the carbide and the action of generating the gas will practically cease until the pressure has become 50 substantially normal, whereupon the oil piston will rise and the water will again attack the carbide. It is found, in practice, that through the use of an oil piston governed by back pressure, substantially uniform 55 generation of the gas will result, with consequent economy in carbide consumption.

The ash of the spent calcium carbide will 60 fall through the perforated bottom of the tray into the base of the vessel 2 whence it may be withdrawn by lifting the valve 5 through the operation of the crank 9. Some water will naturally flow from the vessel 65 with the ash, but this water may be re-

plenished by introducing more water into the top of the vessel. In order that the ash may not become solidified and difficult to remove by gravity flow through the valve opening 3, an agitator 22 is preferably positioned in the base of the vessel and is carried by an operating rod 23 which extends up through the hollow standard 16 and through the pipe 14 to a point above the top thereof. By operating the rod 23, the ash 70 is agitated and stirred up, so as to form a solution adapted to readily flow through the outlet. A shoulder 24, which may be in the form of a nut, precludes the rod and agitator from dropping down and interfering 75 with the operation of the valve 5.

The ash upon leaving the outlet 3 of the vessel may fall into a suitable sink 25 having a sewer connection 26 as shown.

The acetylene gas thus generated, after 80 passing through the valve 21 may be led off for immediate use or storage, but, in practice, I may employ, as a part of the apparatus, purifying and dehydrating means 85 through which the gas is passed before leaving the apparatus. One form which such means may partake is shown as mounted within a casing 27 superimposed on top of the dome 10. Extending across the casing 90 27 and spaced from the bottom is a perforated plate 28 and the pipe 20 may lead from the valve 21 through the wall of the casing, so as to discharge the gas into the casing below the perforated plate. Above 95 the plate there is positioned within the casing a number of sponges 29, while depending from the top of the casing and positioned interiorly thereof is a cup 30 provided with a cover 31. The cup and casing 100 are flanged and bolts 32 pass through said flanges and through the cover 31, in order to provide a gas tight joint.

Substantially the lower half of the cup 30 is adapted to be filled with alcohol or some other suitable purifying agent and into this 110 alcohol the gas, after passing through the perforated plate 28 and circulating through the sponges 29 is adapted to flow through a plurality of goose-neck tubes 33, which are mounted in the base of the cup 30 and have their outlet ends positioned below the surface of the alcohol in the cup. The gas finds exit from the outlet ends of said tubes 33 and after bubbling up through the alcohol passes through a body of wadding 34, 115 which serves to dry the gas before it is discharged through an outlet pipe 35. The perforated partition 36 supports the wadding above the surface of the alcohol.

By passing the gas through the sponges, 120 alcohol and wadding, it is cleansed and dehydrated and is delivered through the outlet pipe 35 in a clean dry condition for any use desired.

Having thus fully described the invention, 125

what I claim as new and desire to secure by Letters Patent is:

1. In a gas generator of the ebb-and-flow type, a container, a member depending thereinto and open at its lower end, said member spaced from the wall of the container, means for supporting carbide within the lower portion of said member, the space below said supporting means communicating with the space between the walls of said member and container, means open at top and bottom and depending within said member with its lower end terminating above said carbide supporting means, and an oil seal, within said member, for said open lower end and serving to automatically control contact of water with the carbide to regulate the generation of gas.
2. In a gas generator of the ebb-and-flow type, an open tank, an inverted bell secured therein, a tube open at both ends and extending vertically through the top of said bell, a carbide container mounted in said bell below the open lower end of the tube, and an oil seal for said open lower end.
3. In a gas generator of the ebb-and-flow type, an open tank, an inverted bell secured

therein, a tube open at both ends and extending vertically through the top of said bell, a carbide container mounted in said bell below the open lower end of the tube, an oil seal for said open lower end, and means beneath the said lower end of said tube to prevent upward escape of gas through said tube.

4. In a gas generator of the ebb-and-flow type, an open tank, an inverted bell secured therein, a tube open at both ends and extending vertically through the top of said bell, a carbide container mounted in said bell below the open lower end of the tube, an oil seal for said open lower end, means beneath the said lower end of said tube to prevent upward escape of gas through said tube, and an agitator disposed beneath the carbide container, with means extended through the said tube and last-named means.

In testimony whereof, I have signed my name to this specification.

RAYMOND R. LIGOT.
